AIRCRAFT FLIGHT INSTRUMENT

Edward R. Dayton, Huntington Station, and Charles J. Bogan, Amityville, N. Y., assignors to Sperry Rand Corporation, Great Neck, N. Y., a corporation of Delaware

Application October 28, 1955, Serial No. 38,611

Term of patent 14 years

(Cl. D52—6)

Fig. 1.

Fig. 2.

Fig. 1 is a front elevation view of an aircraft flight instrument showing our new design; and

Fig. 2 is a side elevational view thereof.

The dominant features of our design are those portions of Figs. 1 and 2 shown in solid lines. The shading of certain elements of the instrument are intended to depict contrasting colors. Also, the stippling is intended to depict color contrast as well as illustrating configuration.

We claim:

The ornamental design for an aircraft flight instrument, as shown and described.
